HYDRAULIC JACK

Guy A. Countryman, Ashland, Ohio

Application September 12, 1935, Serial No. 40,295

9 Claims. (Cl. 60—52)

The invention relates to hydraulic jacks and more particularly to jacks of this type in which the pump is associated with the jack as a unit.

Hydraulic jacks are used not only in an upright position for lifting purposes but in many cases are used in a horizontal or nearly horizontal position in connection with automobile body straightening and repairing tools and the like where it is often necessary to tilt the jack upon its longitudinal axis to such a position that the pump and fluid reservoir therefor are located below the jack proper so that oil will not feed from the reservoir to the pump.

The object of the present improvement is to provide a hydraulic jack so constructed that the fluid will feed from the reservoir to the pump regardless of whether the jack is in upright position or in any horizontal or substantially horizontal position.

A further object is to provide a hydraulic jack having a plurality of spaced communicating channels or passages between the fluid reservoir and pump with gravity operated check valves therein arranged to automatically operate to admit fluid 25 from the reservoir to the pump through the lowermost positioned passage or channel regardless of the position to which the jack may be turned upon its longitudinal axis.

The above objects together with others which will be apparent from the drawings and following description, or which may be later pointed out, may be attained by constructing the improved hydraulic jack in the manner illustrated in the accompanying drawings, in which

Figure 1 is a longitudinal sectional view of a hydraulic jack embodying the invention;

Fig. 2, a transverse detail section on the lines 2—2, Figs. 1 and 3;

Fig. 3, a fragmentary detail section on the line

40 3—3, Fig. 2;

Fig. 4, a fragmentary detail section on the line

4—4, Fig. 2;

Fig. 5, a fragmentary detail section similar to Fig. 4, showing the other passage leading from 45 the oil reservoir to the check valves;

Fig. 6, a plan sectional view of the jack;

Fig. 7, a fragmentary transverse sectional view taken on the line 7—7, Fig. 6;

Fig. 8, a fragmentary transverse sectional view

50 taken on the line 8—8, Fig. 6; and

Fig. 9, a fragmentary sectional view showing the connection of the fluid pipe from the pump to the upper end of the jack cylinder.

Similar numerals refer to similar parts 55 throughout the drawings.

The invention is applicable to any type of hydraulic jack, either single or double acting, but for the purpose of illustration the same is shown as applied to a double acting hydraulic jack of the type disclosed in my prior Patent No. 5 1,985,151, granted December 18, 1934.

The jack may be provided with a base in the form of a casing indicated generally at 10, of substantially oblong shape and provided with the feet 11 and 12 at opposite ends for supporting the same upon the ground or floor in upright position when used for lifting purposes or the like.

An upright annular flange 13 may be located at one end of the base and internally threaded 15 to receive the lower threaded end of the hydraulic jack cylinder 15. The head 16 of the cylinder may be provided with the depending internally threaded flange 17 mounted upon the threaded 20 upper end of the cylinder, and a packing ring 18 25 of inverted substantially channel cross sectional shape may be located within the upwardly disposed annular flange 19 of the head, said packing ring surrounding the ram or piston rod 20 and being held in place as by the screw ring 21. 25

The ram may have a shouldered portion 22 at its lower end portion, the extreme lower end of the ram being reduced and threaded as shown at 23 and having the piston 24 fixed thereon as by the nut 25 which clamps the two fiber or leather 30 washers 26 and the metal disk 27 therebetween.

A boss 29 may be formed upon the base at a point spaced from the annular flange 13, and is provided with an internally threaded socket 30 into which is screwed the lower end of the pump 35 cylinder 31.

The pump is located within an oil reservoir including the shell 33 concentrically located with reference to the pump cylinder and having its lower beveled end 34 received within the annular 40 rib 35 formed upon the top of the base, the inner side of said rib being preferably beveled as at 36 to receive the beveled lower end of the shell.

The head 31 of the reservoir has a central opening 38 surrounding the pump cylinder 31, and a depending peripheral flange 39 internally threaded for engagement with the threaded upper end of the shell 33, which together with the top wall is held clamped upon the base by means of the 50 nut 40 mounted upon the threaded upper portion 41 of the pump cylinder.

The pump plunger 42 is located within the cylinder 31 and provided with the fiber or leather washer 43 at its lower end having the peripheral 55

flange 44, the washer being secured to the lower end of the plunger as by a screw 45.

A stuffing box 46 may be provided at the upper end of the cylinder through which the plunger is 5 slidably received, a nut 47 being fixed to the threaded upper end portion 48 of the plunger. The nut may be provided with ears 49 between which is received the handle lever 50 pivoted to the ears as by the pin 51, the inner end of the 10 lever being pivoted, as at 52, to the upper end of a link 53 pivoted at its lower end, as at 54, upon a lug 55 which may be formed upon the top wall 37 of the reservoir or upon any other suitable portion of apparatus.

15 A port 56 communicates with the lower end of the pump cylinder and leads to a horizontal passage 57 formed in the base casting and plugged at its outer end as by a screw 58, the other end thereof communicating with a vertical passage

20 59. A valve seat 61 is formed in the passage 59 to receive the gravity operated ball 62 which prevents oil from the pump from being forced back into the passage 59 but permits oil to be sucked up through the passage 59 into the pump.

25 A safety valve may be provided to prevent overloading of the jack and as shown, may include a tube 63, closed at its upper end as by the screw plug 64, the lower end of the tube communicating with the passage 59 above the ball 62.

30 A valve seat 65 is formed within the tube 63, the check ball valve 66 being normally held downward thereon as by the coil spring 67, the tension on which may be adjusted by the screw plug 64.

35 Transverse openings 68 in the tube 63 form a communication between the interior of the tube above the valve seat 65, and the interior of the oil reservoir 33. With this construction, if a load greater than the capacity of the jack is placed upon the jack, the ball 66 will be raised by the 40 oil pressure from the pump, permitting the oil to flow through the apertures 68 back into the reservoir, thus preventing undue straining of the jack.

45 A discharge passage 69 communicates with the lower end of the pump cylinder and leads downward through the base 10 communicating with an intermediate portion of the transverse passage 70 which is closed at both ends.

50 As described in my prior Patent No. 1,985,151 above referred to, a valve seat 72 is provided in the passage 69 above the junction with the transverse passage 70 and a check ball valve 73 is normally held seated against the same so as to prevent oil from being sucked upward through the 55 passage 69 into the pump but permitting oil to be forced downward from the pump through the passage 69 to the passage 70.

55 The longitudinally disposed passages 76 and 77 communicate with the transverse passage 70, these passages being each closed at one end and having valve seats 78 and 79 respectively at their open ends to receive the ball valves 80 and 81 respectively, normally urged away from said valve seats as by the coil springs 82.

60 Transversely disposed chambers 83 and 84 communicate with the open ends of the passages 76 and 77 respectively and with the inlet ports 85 and 86 leading to the lower and upper ends 70 respectively of the hydraulic cylinder 15, the upper port 86 communicating with the vertical pipe 86a which leads to a radial inlet port 88 terminating in the vertical passage 89 formed in the head 16 and adapted to admit oil into the 75 upper end of the cylinder 15 above the piston 22

and also to hold the packing ring 18 under pressure.

5 A pair of screw plugs 90 and 91 are mounted in internally threaded openings axially located with reference to the passages 76 and 77 respectively, each of said screw plugs having a central bore 92 communicating with a plurality of radial passages 93, the outer ends of which communicate with an annular groove 94 in the peripheral portion of the screw plug, ports 95 and 96 forming communication between the grooves of the screw plugs 90 and 91 respectively and the oil reservoir 33.

10 The bore 92 of each of the screw plugs communicates with the corresponding transverse passage 83 or 84, the screw plugs being provided at their ends with valve seats 97 and 98 respectively adapted to receive the ball valves 80 and 81 respectively.

15 A portion of the bore of each screw plug is threaded to receive the threaded portions 99 of the valve stems 87 and 87a, which are adapted to contact with the balls 80 and 81 respectively for the purpose of moving said balls away from the seats 97 and 98 and toward the seats 78 and 79. The stems 87 and 87a are preferably arranged to be simultaneously operated in reverse directions and this may be accomplished by means of gears fixed upon the stems and meshing with each other. For the purpose of operating the stems, a handle may be provided upon one stem whereby rotation thereof, through the gears, will operate both stems in opposite directions.

20 All of the above described parts are disclosed in my prior patent above referred to and in themselves form no part of the present invention, being merely for the purpose of illustrating a complete hydraulic jack.

25 The invention pertains to means located in the intake to the pump from the reservoir and as shown, the intake passage 59 communicates at its lower end with a pair of oppositely disposed, outwardly and downwardly inclined passages 100 and 101, each of which is enlarged at its outer end as shown at 102 and closed as by a screw plug 103. A valve seat 104 is formed in each of the enlarged portions of these passages, a check ball valve 105 being located in the enlarged portion of each passage and arranged to cooperate with the corresponding valve seat 104.

30 As best shown in Fig. 2, the passages 100 and 101 are located substantially at a 45° angle through the base and the enlarged portions of the passages 100 and 101 communicate with the upwardly inclined passages 106 and 107 respectively, leading to the lower end of the oil reservoir with which they communicate at opposite sides of the center thereof, the points of communication being oppositely offset from the center as shown in Fig. 2.

35 In the operation of the jack, it should be noted that with the jack standing in upright position, both of the check balls 105 will be located at the outer ends of the enlarged portions 102 of the passages 100 and 101, and a considerable distance away from the valve seats 104. As the pump plunger is operated, on the upstroke oil is drawn from the reservoir through the passages 106 and 107 and then through the passages 100 and 101 upward through the passage 59 and then through the horizontal passages 67 to the intake passage 56, filling the pump cylinder.

40 On the downstroke of the pump plunger the ball 62 will be forced down upon the seat 61, closing the passage 59, the oil being forced down

through the passage 69 and through the transverse passage 70 and then to one or the other of the jack intake passages 85 or 86, depending upon the position of the valves which control 5 these intake passages.

If the jack is moved to a horizontal or nearly horizontal position, one or the other of the intake passages 106 or 107 will be located below the oil level in the reservoir 33 so as to feed oil 10 from the reservoir to the pump, the other passage being automatically closed by means of the corresponding check ball 105. For instance, as shown in Fig. 2, the intake passage 106 would be located below the oil level in the reservoir while 15 the passage 107, which may be located above the oil level, is cut off from communication with the pump by means of the corresponding ball 105 seating against its valve seat 104, preventing the pump from sucking air from the reservoir 20 through this passage.

Thus, as the jack is rotated upon its horizontal axis to any desired or necessary position, the ball 105 of the lower most positioned passage 100 or 101 will by gravity fall away from its valve seat 25 while the ball controlling the other passage will by gravity seat upon its valve seat, leaving the lowermost passage in communication with the pump and cutting off the uppermost passage from communication with the pump.

30 Although the invention has been illustrated and described as applied to the particular type of double acting hydraulic jack illustrated in my prior Patent No. 1,985,151, it should be understood that the invention is equally well adapted 35 to any form of hydraulic jack either single or double acting, it only being necessary that the series of passages and valves illustrated in Figs. 2, 3 and 4 be located between the intake port to the pump and the discharge from the oil reservoir in the manner illustrated and described 40 herein.

I claim:

1. A hydraulic jack including a cylinder, a ram in the cylinder, a pump, parallel to the jack 45 cylinder, a passage forming communication between the pump and the cylinder, a fluid reservoir parallel to the pump, opposed, transversely disposed passages below the fluid reservoir communicating with the pump at their inner ends and closed at their outer ends, said passages being located in a plane at an angle of substantially 45° to the plane in which the axes of the jack cylinder and fluid reservoir are located, gravity 50 check balls in said passages, and passages communicating with intermediate portions of the last named passages and with the fluid reservoir at opposite sides of the center thereof.

2. A hydraulic jack including a cylinder, a ram in the cylinder, a pump parallel to the jack cylinder, a passage forming communication between the pump and the cylinder, a fluid reservoir parallel to the pump, opposed, downwardly and outwardly inclined, transversely disposed passages below the fluid reservoir communicating with the pump at their inner ends and closed at their outer ends, said passages being located in a plane at an angle of substantially 45° to the plane in which the axes of the jack cylinder and fluid reservoir are located, gravity check balls in said 55 passages, and passages communicating with intermediate portions of the last named passages and with the fluid reservoir at opposite sides of the center thereof.

3. A hydraulic jack including a cylinder, a ram 60 in the cylinder, a pump parallel to the jack cylinder, a passage forming communication between the pump and the cylinder, a fluid reservoir parallel to the pump, opposed, angularly located, transversely disposed passages below the fluid reservoir communicating with the pump at their inner ends and closed at their outer ends, said 65 passages being located in a plane at an angle of substantially 45° to the plane in which the axes of the jack cylinder and fluid reservoir are located, gravity check balls in said passages, and angularly inclined 70 passages communicating with intermediate portions of the last named passages and with the fluid reservoir at opposite sides of the center thereof.

der, a passage forming communication between the pump and the cylinder, a fluid reservoir parallel to the pump, opposed, angularly located, transversely disposed passages below the fluid reservoir communicating with the pump at their inner ends and closed at their outer ends, said 5 passages being located in a plane at an angle of substantially 45° to the plane in which the axes of the jack cylinder and fluid reservoir are located, gravity check balls in said passages, and 10 passages communicating with intermediate portions of the last named passages and with the fluid reservoir at opposite sides of the center thereof.

4. A hydraulic jack including a cylinder, a ram in the cylinder, a pump parallel to the jack cylinder, a passage forming communication between the pump and the cylinder, a fluid reservoir parallel to the pump, opposed, angularly located, downwardly and outwardly inclined, transversely disposed 15 passages below the fluid reservoir communicating with the pump at their inner ends and closed at their outer ends, said passages being located in a plane at an angle of substantially 45° to the plane in which the axes of the jack cylinder and fluid reservoir are located, gravity check balls in said passages, and 20 passages communicating with intermediate portions of the last named passages and with the fluid reservoir at opposite sides of the center thereof.

5. A hydraulic jack including a cylinder, a ram in the cylinder, a pump parallel to the jack cylinder, a passage forming communication between the pump and the cylinder, a fluid reservoir parallel to the pump, opposed, transversely disposed 25 passages below the fluid reservoir communicating with the pump at their inner ends and closed at their outer ends, said passages being located in a plane at an angle of substantially 45° to the plane in which the axes of the jack cylinder and fluid reservoir are located, gravity check balls in said 30 passages, and angularly inclined passages communicating with intermediate portions of the last named passages and with the fluid reservoir at opposite sides of the center thereof.

6. A hydraulic jack including a cylinder, a ram in the cylinder, a pump parallel to the jack cylinder, a passage forming communication between the pump and the cylinder, a fluid reservoir parallel to the pump, opposed, downwardly and outwardly inclined, transversely disposed 35 passages below the fluid reservoir communicating with the pump at their inner ends and closed at their outer ends, said passages being located in a plane at an angle of substantially 45° to the plane in which the axes of the jack cylinder and fluid reservoir are located, gravity check balls in said 40 passages, and angularly inclined passages communicating with intermediate portions of the last named passages and with the fluid reservoir at opposite sides of the center thereof.

7. A hydraulic jack including a cylinder, a ram in the cylinder, a pump parallel to the jack cylinder, a passage forming communication between the pump and the cylinder, a fluid reservoir parallel to the pump, opposed, angularly located, transversely disposed 45 passages below the fluid reservoir communicating with the pump at their inner ends and closed at their outer ends, said 50 passages being located in a plane at an angle of substantially 45° to the plane in which the axes of the jack cylinder and fluid reservoir are located, gravity check balls in said 55 passages, and angularly inclined 55 passages communicating with intermediate portions of the last named passages and with the fluid reservoir at opposite sides of the center thereof.

portions of the last named passages and with the fluid reservoir at opposite sides of the center thereof.

8. A hydraulic jack including a cylinder, a ram 5 in the cylinder, a pump parallel to the jack cylinder, a passage forming communication between the pump and the cylinder, a fluid reservoir parallel to the pump, opposed, angularly located, downwardly and outwardly inclined, transversely 10 disposed passages below the fluid reservoir communicating with the pump at their inner ends and closed at their outer ends, said passages being located in a plane at an angle of substantially 45° to the plane in which the axes of the jack cylinder and fluid reservoir are located, gravity check 15 balls in said passages, and angularly inclined passages communicating with intermediate portions of the last named passages and with the fluid reservoir at opposite sides of the center thereof.

9. A hydraulic jack including a cylinder, a ram in the cylinder, a pump parallel to the jack cylinder, a passage forming communication between the pump and the cylinder, a fluid reservoir parallel to the pump, opposed, transversely disposed 5 passages below the fluid reservoir communicating with the pump at their inner ends and closed at their outer ends, said passages being located in a plane at an angle of substantially 45° to the plane in which the axes of the jack cylinder and fluid 10 reservoir are located, gravity check balls in said passages, a check valve between said passages and the pump, and passages communicating with intermediate portions of the last named passages and with the fluid reservoir at opposite sides of 15 the center thereof.

GUY A. COUNTRYMAN.
